UNITED STATES PATENT OFFICE.

BURCHARD THOENS, OF NEW YORK, N. Y.

MEANS FOR PROPELLING VEHICLES.

1,121,419.

Specification of Letters Patent. Patented Dec. 15, 1914.

Application filed March 20, 1914. Serial No. 826,131.

To all whom it may concern:

Be it known that I, BURCHARD THOENS, a citizen of the United States, and resident of New York, county and State of New York, have invented certain new and useful Improvements in Means for Propelling Vehicles, of which the following is a specification.

My invention relates to a means for propelling vehicles of any desired character, as for instance water or land vehicles, and consists of means and apparatus whereby to render available the atmospheric pressure upon the face of what I term "bulwark" secured to the vessel in any desired position, that is, an extended plate presenting a surface of large area and so supported as to be movable with and constitute practically a part of the vehicle, with means of securing a preponderating pressure upon either side of the bulwark, as fully set forth herein-after and as illustrated in the accompanying drawing, in which:

Figures 1 and 2 are diagrams illustrating perspectively the principle of operation embodied in my invention; Fig. 3 is a side elevation of one apparatus which may be employed in carrying out my invention; Fig. 4 is a section on the line 4—4 Fig. 3; Fig. 5 is an end view of the structure shown in Fig. 3; Fig. 6 is a view illustrating the arrangement when a single bulwark is used; and Fig. 7 is an elevation of one form of vehicle showing this invention applied thereto.

Before describing the details of the apparatus which may be used in carrying out my improvement I will refer to the diagrammatic illustrations Figs. 1 and 2 in explaining the principle of operation of my invention.

Let it be assumed that *a* is a rotatable shaft supported in suitable bearings and connected with means for rotating it at a high speed, and that *b* is a fan carried by such shaft and of such a construction that its rotation will result in the rapid dispersion radially of the air which is brought in contact with the blades of the fan. If now a plate or shield *d* is brought to either side of the said fan the result of the exhausting action of the latter upon the air will be to decrease the atmospheric pressure upon that face of the shield adjacent to the fan, and there will be a preponderating pressure upon the other or outside face of the shield.

If now the aforesaid parts are assumed to be mounted upon any kind of vehicle, as for instance a vessel floating upon the water, and the shield *d* is secured thereto or held thereon so that the two must move together, the resulting pressure upon the outer face of the shield, that is the face outside that which is proximate to the fan, will result in propelling the vessel. If further it be assumed that there are two such shields *d*, *d*, upon the vessel, and that the fan is capable of being shifted from a position opposite the inner face of one shield to a position opposite the inner face of the other, the preponderating air pressure will be upon the outer face of one or the other of the shields, with a corresponding change in direction of propulsion of the vessel with which the shields are connected.

The above principle of operation may be embodied in structures of varied character and arrangement, one of which is represented in the remaining figures of the drawing where *X* represents the deck of a vessel, to which is bolted a suitable framework *B* having bearings for the shaft *a*, and parallel guides *e* of any suitable character, upon which are supported one or more parts corresponding in effect to the aforesaid shields *d*, but to which I apply the term "bulwarks" as they are necessarily strong and must receive the pressure of the air which constitutes the propelling agent, and transmit it to the vessel to be propelled thereby. Upon the shaft *a* is supported one or more fans *b*, and also a band-pulley *f*, receiving a belt *g*, which constitutes means of transmitting movement to the shaft from a suitable motor, not shown, supported within the vessel or other vehicle. If there is but a single bulwark it may be secured in a stationary position upon the vessel Fig. 6, but where there is a plurality of bulwarks they are supported to slide upon the guides *e*, and consist each of a suitable frame *h* carrying plates of boiler iron *i*, and the frames *h* are suitably connected together as by beams *m*, so that the bulwarks may be carried simultaneously to and from the respective fans. One means of shifting the movable parts consists of a crank shaft *n*, to each of two cranks *k* of which is jointed a connecting rod *q* slotted at the opposite end to receive the rocking bearing of a trunnion *r*, upon any part of the sliding frame supporting the bulwarks, with springs *s* between the bearing and the

ends of the slot in the connecting rod which serve to prevent shock in transmitting motion. As shown the shaft *n* carries a worm-wheel *t* which gears with a worm *u* upon a shaft *v*, the rotation of which will serve not only to transmit motion to the frame carrying the bulwarks, but also serve as a locking device to hold the parts in place, but any other suitable means for locking and holding them after adjustment may be employed, provided it is strong enough to resist the pressure of the air upon the bulwarks.

It will be seen that the air pressure will be in proportion to the surfaces exposed by the bulwarks, and that by multiplying the bulwarks and correspondingly multiplying the fans there will be a corresponding increase of available power for propulsion. It will further be seen that by thus mounting the bulwarks so as to be movable to and from the respective fans the direction in which the pressure is brought upon the bulwarks, that is the sides exposed to the air pressure, will be changed.

I have illustrated the above only as one embodiment of the principle of my invention, and it will be evident that the invention may be applied operatively in various ways, and that with various structures either the bulwarks or the fans may be shifted, and that the parts may be applied with the bulwarks transverse to the vessel for the purpose of propelling it longitudinally or parallel to the keel for the purpose of moving it laterally to aid in steering or changing the course.

In Fig. 6 the shaft slides and carries two fans either of which may be brought adjacent to the bulwark, the shaft carrying a long pinion 2 gearing with a spur wheel 3 suitably driven.

Fig. 7 shows the invention applied to one form of vehicle, in this case a motor boat. The boat is provided with a motor or engine *A*, which may be of the hydrocarbon type, which drives the shaft *a* of the propelling device which is mounted at any suitable position on the boat. By means of this mechanism the boat may be driven either forwardly or backwardly by manipulating the handle or hand-wheel which shifts the bulwark or fans into and out of operating position.

While the invention is shown as applied to a motor boat it is to be understood that this application is merely illustrative since the invention may be applied to all types of vehicles.

Without limiting myself to the means set forth for carrying out my invention, I claim:

1. In a means for propelling vehicles, the combination with a bulwark on said vehicle, of means for exhausting the air at will from one or the other side of said bulwark.

2. In a means for propelling vehicles the combination with parallel separated bulwarks erected on said vehicle, of means for exhausting air from either of the proximate faces of said bulwarks.

3. The combination with a vehicle of a transverse bulwark projecting outward from said vehicle, of means for securing at one side or the other of said bulwark at will a preponderating air pressure.

4. The combination with a vehicle of a transverse bulwark, projecting outward from said vehicle, of rotatable fans, and means to cause the fans to secure at one side or the other of said bulwark a preponderating air pressure.

5. The combination with a vehicle of parallel separated transverse bulwarks and an intermediate rotatable fan, and means to cause the fan to exhaust the air from either of the proximate faces of the bulwarks.

6. The combination with a vehicle of parallel separated transverse bulwarks and an intermediate rotatable fan, and means for shifting one of said members to cause the fan to exhaust the air from either of the proximate faces of the bulwarks.

7. The combination with a vehicle of two separated parallel bulwarks and an intermediate rotatable fan, and means for carrying the bulwarks to and from the fan for the purpose specified.

8. The combination with a vehicle of a rotatable shaft, means for driving the same, a fan thereon, bulwarks supported to be movable to and from the fan, and means for securing them in position after adjustment.

9. The combination with a vehicle of a rotatable shaft, means for driving the same, a plurality of fans thereon, bulwarks supported to be movable to and from each fan, and means for securing them in position after adjustment.

10. The combination with a vehicle of a frame provided with bearings and guides, a shaft rotatable in said bearings, and a fan on said shaft, bulwarks supported on said guides, and means for moving the bulwarks to and from the fan.

11. The combination with a vehicle of a frame provided with bearings and guides, a shaft rotatable in said bearings, and a fan on said shaft, bulwarks connected together supported on said guides, and means for moving the bulwarks to and from the fan.

12. The combination with a vehicle of a frame provided with bearings and guides, a shaft rotatable in said bearings and a plurality of fans on said shaft, bulwarks supported to slide on the guides to and from the fans, and means for shifting and securing in place the said bulwarks.

13. A propelling structure consisting of a frame having bearings and guides and adapted for application to a vehicle, a shaft

rotatable in bearings of the frame, a fan on said shaft, and a bulwark movable on said guides to and from the fan for the purpose set forth.

5 14. A propelling structure consisting of a frame having bearings and guides and adapted for application to a vehicle, a shaft rotatable in bearings of the frame, a plurality of fans on said shaft, and a plurality of bulwarks movable in said guides to and from the fans for the purpose set forth.

10 15. A propelling structure consisting of a frame having bearings and guides and adapted for application to a vehicle, a shaft rotatable in bearings of the frame, a plurality of fans on said shaft, and a plurality of connected bulwarks movable in said guides to and from the fan for the purpose set forth.

15 20 16. In a vehicle, the combination with a

bulwark on said vehicle, of means for exhausting the air from one side of said bulwark to cause a preponderating air pressure on the other side of said bulwark, and means for placing said bulwark and said means in 25 and out of operative relation.

17. In a vehicle, the combination with a bulwark, of a fan for exhausting the air from one side of said bulwark to cause a preponderating air pressure on the other 30 side of said bulwark, and means for moving said fan and bulwark relatively to each other.

In testimony whereof I affix my signature in presence of two witnesses.

BURCHARD THOENS.
